UNITED STATES PATENT OFFICE.

JOSEPH ARTHUR GORTON, OF MONTCLAIR, NEW JERSEY.

VALVE

1,002,835.

Specification of Letters Patent. Patented Sept. 12, 1911.

Application filed April 29, 1910. Serial No. 558,404.

To all whom it may concern:

Be it known that I, JOSEPH A. GORTON, a citizen of the United States, and a resident of Montclair, in the county of Essex and State of New Jersey, have invented certain new and useful Improvements in Valves, of which the following is a specification.

My invention relates broadly and generally to new and useful improvements in valves, and more particularly to valves of that character or type known as turning plugs, in which a valve body provided with a suitable passage or port is rotatably mounted in a seat and is adapted to be rotated relative to a ported casing or conduit to control a flow therethrough, the flow being established when the ports in the valve body and the casing are brought into communication and discontinued when the communication is broken. In all prior constructions of which I am aware it has been difficult to produce a satisfactory valve proof against leakage for the reason that uneven wear exists between the valve and its seat which destroys a close fit between the parts and causes leakage, particularly when the body is operated to cut off the flow. This objection has been due largely to the fact that the operating stems of the valve body have been so connected thereto that any tendency to deflect the stem from its proper position when operating it, would cause a corresponding greater pressure between the valve and its seat at one point, causing greater wear of the parts at that point, destroying the required fit between the valve and its seat and resulting in leakage.

It is, therefore, the object of my invention to provide a novel form of connection between the valve body and its operating means, whereby the valve when once adjusted or fitted to its seat, will not be disturbed so as to destroy its proper fit, should the valve stem be deflected during the operation of the valve.

The invention consists in the improvements to be fully described hereinafter and the novelty of which will be particularly pointed out and distinctly claimed.

I have fully and clearly illustrated my invention in the accompanying drawings to be taken as a part of this specification and wherein—

Figure 1 is a longitudinal sectional view through a valve constructed in accordance

with my invention; Fig. 2 is a transverse sectional view taken on a line to one side of the valve body or plug; Fig. 3 is a detail sectional view of the connection between the stem and valve body taken on the line 3—3 of Fig. 1.

Referring to the drawings by characters of reference, A designates generally a valve casing consisting of the shell or chamber 1, with which communicate alining internally threaded nipples 2, 2, by means of which the valve casing may be secured to pipes through which the flow is to be controlled. This chamber or casing is formed with a downwardly tapering seat 3 opening through the side thereof as at 4, said opening being surrounded by an internally threaded annular flange 5, into which is threaded a closure cap or bonnet 6 for the chamber, the bottom of the tapering seat terminating in a pocket 7 in the side wall of the chamber opposite to the opening 4.

Rotatably seated in the tapering seat 3, and tapered to correspond thereto so as to closely fit said seat at all points, is a valve body or plug 8, formed with a transverse opening or passage 9 adapted to be brought into communication with the nipples 2, 2 to permit flow from one nipple to the other through the valve casing. It will be understood that the sides of the plug which bound the passage 9 are adapted, upon rotation of the said plug, to be brought into position to close the passage through the valve casing to cut off flow from one nipple to the other. The lower end of the valve body projects into the pocket 7, and when first fitted into place is spaced from the bottom of said pocket so that as the seat and valve wear the latter may have clearance to permit it to settle closely to the seat and thereby insure a close fit at all times.

Extending through the bonnet 6 and in longitudinal alinement with the valve body 108 8 is the valve operating member shown in the form of a stem 10 adapted to be operated by means of a hand lever 11 rigidly secured to the end of said stem exterior to the valve casing. Suitable means may be employed 105 for packing the stem as, for instance, a packing washer or ring 12, surrounding the stem and arranged between a flange 13 in the neck 14 of the bonnet, and a packing nut 15 surrounding the stem and threaded onto the neck of the bonnet. Means is provided for connecting or coupling the valve body or

plug and this member 10 in such a manner as to permit relative lateral movement of the stem to the valve plug, said coupling being flexible in nature and effect when the 5 stem is moved laterally relative to the valve body, but adapted upon rotation to positively rotate the valve. I will now describe the embodiment which I have illustrated for accomplishing the result stated.

10 Upon the lower end of the valve stem I provide a head 16, which may be circular in form and having a substantially flat transverse under face in a plane transversely of the stem, and provide said head with a plurality of rigid projections or fingers 17, spaced apart from each other circumferentially of the head to provide two straight-away intersecting recesses 18, 19; extending entirely across the face of the said head at 15 right angles to each other. Carried by the top of the valve body 8 is a similar head 20 having a substantially flat upper face and provided with circumferential projections 21 arranged to fit into the recesses 18, 19 of 20 the head on the stem, and having spaces or recesses between said projections 21 to receive the projections 17 on the stem, the said projections on stem and valve being adapted to interlock and engage upon rotation of the 25 stem so as to impart rotation to the valve. In order that the valve stem may have the desired sliding, rocking and wobbling movement on the valve I preferably make the recesses of greater width than the projection 30 so that the projections fit loosely in said recesses whereby there will be clearance between the side faces of the projections and between the ends of the projections and the bottoms of the recesses. The ends of the 35 projections are held clear of the bottoms of the recesses by a spacing block 22 which may be integral with the head on the valve and located centrally thereof equi-distant between the projections 21 and spaced laterally 40 therefrom and from the projections on the stem, and upon which the transverse flat under face of the head 16 slidably engages and rocks, said block projecting beyond the 45 ends of the projections 21 as shown in Fig. 50 1. By this form of joint or coupling between the stem and valve body it will be seen that the stem is free to be bodily deflected laterally relative to the valve body in any direction, to wobble freely without destroying the proper fit between said body and its 55 seat and the parts may also slide transversely of each other.

In order to maintain proper interengagement of the coupling members at all times 60 and to forcibly urge the valve body to its seat, I provide an expansive coil spring 23, mounted on the valve stem and exerting its force expansively against the head of the bonnet and the head 16 to thrust the stem toward the valve body into engagement with

the block or post 22, and thereby urge the valve to its seat.

I preferably, although not necessarily, form the valve body of a composition of bakelite, vulcanized asbestos and graphite, 70 molded into the desired shape, and secure the head 20 thereto by anchoring arms 24, which are anchored in the valve when the latter is molded, all arranged as shown clearly in dotted lines in Fig. 2. 75

The invention will be found desirable in that it provides for a ready assemblage of the parts without the necessity of any particular adjustment to insure the proper fit of the valve to its seat, as the valve may be 80 dropped or placed into its seat and the stem interengaged therewith, a deflection of the stem from exact alinement with the valve in no way disturbing the latter and at the same time a proper connection being provided between the parts. 85

Having thus described my invention, what I claim as new and desire to secure by Letters Patent is:—

1. In combination, a valve having spaced 90 projections, and an operating member having spaced projections interengaging those on the valve, one of said members having a substantially flat transverse face, and a spacer between said members engaging said 95 face to provide clearances between the interengaging projections, said valve and operating member being slideable transversely of each other and said spacer being slideable across said flat face. 100

2. In combination, a valve having spaced 105 projections and an operating member having spaced projections interengaging with those on the valve, one of said members having a substantially flat transverse face located between the projections thereon, and a spacer carried by the other of said members and located between the projections thereon and spaced laterally from the projections on the opposite member, said spacer 110 engaging said flat face, whereby the valve and its operating member are transversely slideable relative to each other. 115

3. In combination, a valve having spaced 120 projections and an operating member having spaced projections interengaging those on the valve, one of said members having a substantially flat transverse face located between the projections thereon, and a spacer carried by the other of said members and located centrally between the projections thereon and spaced laterally from the projections on the opposite member, said spacer 125 projecting beyond the ends of the projections on the member upon which it is carried into engagement with said flat face to provide clearances between the projections, whereby the valve and its operating member are transversely slideable relative to each other and one can rock in the other. 130

4. In combination, a valve having spaced projections and intersecting recesses, said recesses extending across the valve at right angles to each other, an operating member having similar projections and intersecting spaces interengaging those of the valve, one of said members having a substantially flat transverse face located between said projections and a spacer on the other of said members at the intersection of said spaces and spaced laterally from the projections on said members and projecting beyond the projections on the member on which it is carried to engage the flat face of the other member.
5. In combination, a valve having circumferentially spaced projections and an operating member having correspondingly spaced projections interengaging those on the valve, one of said members having a substantially flat transverse face located between the projections thereon, and a spacer carried by the other of said members and located centrally face to provide clearances between the projections thereon, and spaced laterally from the projections on the opposite member, said spacer projecting beyond the ends of the projections on the member upon which it is carried and into engagement with said flat face to provide clearances between the projections whereby the valve and its operating member are transversely slideable relative to each other, and one can rock on the other.
6. In combination, a valve having circumferentially arranged spaced projections forming intersecting recesses extending across the valve at right angles to each other, and an operating member having projections and recesses corresponding respectively to the recesses and projections on the valve and interengaging the same, said recesses being of greater width than the projections, the intersecting recesses on one of said members forming a substantially flat transverse face at the center portion of said member, and a spacer pin on the other of said members and located centrally thereof between, and spaced laterally from the projections thereon and the projections on the other member and extending beyond the ends of the projections on its member into engagement with the transverse face on the other member to provide clearances between the ends of the projections and the bottoms of the recesses, whereby the valve and its operating member are transversely slideable relative to each other, and one can rock on the other.

In testimony whereof I have signed my name to this specification in the presence of two subscribing witnesses.

Correction in Letters Patent No. 1,002,835.

It is hereby certified that in Letters Patent No. 1,002,835, granted September 12, 1911, upon the application of Joseph Arthur Gorton, of Montclair, New Jersey, for an improvement in "Valves," an error appears in the printed specification requiring correction as follows: Page 3, line 23, strike out the words "face to provide clearances between" and insert the words *between and spaced laterally from*; and that the said Letters Patent should be read with this correction therein that the same may conform to the record of the case in the Patent Office.

Signed and sealed this 3d day of October, A. D., 1911.

E. B. MOORE,

Commissioner of Patents.

4. In combination, a valve having spaced projections and intersecting recesses, said recesses extending across the valve at right angles to each other, an operating member having similar projections and intersecting spaces interengaging those of the valve, one of said members having a substantially flat transverse face located between said projections and a spacer on the other of said members at the intersection of said spaces and spaced laterally from the projections on said members and projecting beyond the projections on the member on which it is carried to engage the flat face of the other member.
5. In combination, a valve having circumferentially spaced projections and an operating member having correspondingly spaced projections interengaging those on the valve, one of said members having a substantially flat transverse face located between the projections thereon, and a spacer carried by the other of said members and located centrally face to provide clearances between the projections thereon, and spaced laterally from the projections on the opposite member, said spacer projecting beyond the ends of the projections on the member upon which it is carried and into engagement with said flat face to provide clearances between the projections whereby the valve and its operating member are transversely slideable relative to each other, and one can rock on the other.
6. In combination, a valve having circumferentially arranged spaced projections forming intersecting recesses extending across the valve at right angles to each other, and an operating member having projections and recesses corresponding respectively to the recesses and projections on the valve and interengaging the same, said recesses being of greater width than the projections, the intersecting recesses on one of said members forming a substantially flat transverse face at the center portion of said member, and a spacer pin on the other of said members and located centrally thereof between, and spaced laterally from the projections thereon and the projections on the other member and extending beyond the ends of the projections on its member into engagement with the transverse face on the other member to provide clearances between the ends of the projections and the bottoms of the recesses, whereby the valve and its operating member are transversely slideable relative to each other, and one can rock on the other.

In testimony whereof I have signed my name to this specification in the presence of two subscribing witnesses.
